UNITED STATES PATENT OFFICE.

JOHN R. ROGERS, OF NEW YORK, N. Y., ASSIGNOR TO MERGENTHALER LINOTYPE COMPANY, A CORPORATION OF NEW YORK.

LINOTYPE-MACHINE.

No. 846,054.

Specification of Letters Patent. Patented March 5, 1907.

Application filed September 24, 1906. Serial No. 835,960.

To all whom it may concern:

Be it known that I, JOHN R. ROGERS, of Brooklyn, New York city, county of Kings, and State of New York, have invented a new and useful Improvement in Linotype-Machines, of which the following is a specification.

My invention has reference to an improved escapement device for releasing shouldered matrices one at a time from a channeled magazine.

It relates to that class of escapements wherein a centrally-pivoted lever is provided at opposite ends with shoulders or pawls, which are projected alternately into the magazine and into the path of the matrices, so that when the foremost matrix is released the next one is permitted to assume its place, as represented, for example, in Letters Patent of the United States Nos. 392,446 and 436,532.

The aims of the invention are to lengthen the life of the escapement, to render its action certain regardless of the speed at which it is moved, to cheapen and simplify the construction, and to lessen the wear on the matrices.

To this end it consists in a centrally-pivoted escapement-lever carrying at opposite ends shoulders or pawls which are separated a distance greater than the length of a matrix.

Heretofore in all escapements of this class the operative length—that is to say, the distance between the outer sides of the two active shoulders or pawls—has been less than the distance between the ears at the opposite ends of the matrices. In constructing my escapement I give the same a greatly-increased length in proportion to the length of the matrices, the distance between the two pawls or shoulders being greater than the entire length of a matrix, this change resulting in a marked change in their mode of action on the matrices.

In the drawings, Figures 1, 2, 3, and 4 are vertical sections through a magazine containing matrices and provided with my improved escapement. Fig. 1 illustrates the normal positions of the parts, and the following figures the successive positions which the parts assume in releasing one matrix and permitting the next to take its place. Fig. 5 is a perspective view showing the slot in the under side of the magazine to admit the es-

capement shoulders. Fig. 6 is a vertical cross-section through the lower end of the magazine, showing the relation of the escapements to the magazine-plates and the grooves therein. Fig. 7 is a vertical cross-section through one of the magazines on the line 6—6, Figs. 1 and 5, illustrating the manner in which escapements of uniform width may be used with channels of different widths.

Referring to the drawings, A represents an inclined magazine consisting of parallel top and bottom plates, having their inner faces provided with longitudinal channels or grooves a to receive and guide the ears or edges of the matrices.

B represent the matrices, each consisting of a flat plate having the matrix character in one edge and also having on each of its longitudinal edges lips or ears b b at opposite ends.

The magazine and matrices as shown are of the ordinary construction shown in United States Patent No. 436,532 and used in the commercial Mergenthaler machines of the present day.

The escapements are required to release the matrices from the respective channels one at a time in the order of selection and to permit them to pass downward by gravity out of the lower end of the magazine through the usual channel-plate or raceway C to the assembling devices.

D represents my improved escapement consisting in the preferred form of a lever mounted on a central pivot d and having at opposite ends two integral upright shoulders or dogs d' and d'', which are projected upward alternately into the magazine and into the paths of the matrices by the vibration of the escapement.

The escapements are pivoted in grooves in the top of the underlying plate E, which may be sustained on the main frame or secured to the magazine, as preferred. Each escapement is acted upon at the upper end by a lifting-spring F, which causes the shoulder d'' to stand normally within the magazine. The position of the escapement may be reversed by any suitable device—such, for example, as a vertical slide G, mounted in the main frame in position to rise beneath the lower end of the escapement. These rods G may be connected in any suitable manner with finger-keys or actuating devices under the

control of finger-keys, various mechanisms suitable for the purpose being well known in the art.

It is to be particularly noted that my escapement-lever between the operative ends or shoulders is of a length greater than that of a matrix, the distance between the shoulders d' and d^2 being preferably about one and one-half times the over-all length of a matrix. Owing to this fact and to the fact that the upper shoulder d^2 of the escapement is held normally in the elevated position, (shown in Fig. 1,) the foremost matrix is retained at rest within the magazine by said upper escapement-shoulder, bearing beneath or in front the upper or rear ear b' of the matrix. When the position of the escapement is reversed, the upper shoulder d^2 is withdrawn and the matrix permitted to pass thereover, as shown in Fig. 2, the lower shoulder d' of the escapement being at the same time raised, so that the advancing matrix finally contacts at its forward end with said shoulder d' , whereby it is temporarily arrested in the manner shown in Fig. 3. During this action the foremost matrix advances about one-half its length. It is followed by the second matrix, which rests against the first with its upper ear b' some distance behind the rear shoulder d^2 of the escapement. The escapement is speedily released and permitted to assume its first position, as shown in Fig. 4, the effect being to withdraw the forward shoulder d' , so that the foremost matrix may escape thereover, while at the same time the advancing second matrix is arrested by the rear escapement-shoulder d^2 , which is raised within the magazine in advance of the matrix-ear b' . It is to be observed that when the parts are in their normal positions the foremost matrix is held at rest by the engagement of its upper or rear end with the upper or rear shoulder of the escapement and that when the position of the escapement is reversed to release the foremost matrix the latter is arrested momentarily by contact with the lower or forward end d' of the escapement, which acts against the outer end of the matrix. When the escapement resumes its original position, its upper end engages the upper ear of the second matrix.

It will be seen that each matrix is released by two successive movements and that the upper ear of each matrix engages but once with the escapement. In escapements of this class as heretofore constructed the rear matrix-ear b' encountered the two shoulders of the escapement successively, so that this ear was subjected twice to the wear and impact due to the momentum of the advancing column of matrices. The present construction therefore reduces by one-half the wear and the blows against the ear of the matrix. As this ear is relied upon to secure the proper

alignment of the composed matrices in front of the mold, the reduction in wear is of great importance.

As the released matrices descend by gravity and at varying rates of speed under different conditions and as there is occasional variation in the speed of the escapement, it is of great importance that the greatest possible latitude should be allowed in the movement of the escapement, so that the foremost matrix may have ample time to escape and the second matrix have ample time to assume the position vacated by the first without danger of the escapement-shoulders striking the outer edges of the matrix-ears or of their failing to properly engage the same. By giving the escapement the increased length in the manner shown and described, so that the time required for the passage of a matrix from its upper to its lower end is increased, I am enabled to operate the machine at high speed and to release the matrices in quick succession without danger of the failure of the parts to operate in the proper manner. Another advantage resulting from the increased length of the escapements is the fact that the paths of the shoulders have less curvature than they would have if a short escapement were used. It is desirable that the shoulders should move as nearly as possible at right angles to the path in which the matrices move, this in order to reduce the wear of the matrix-ears and to lessen the danger of their being given a beveled or rounded form by the wear of the escapements thereon. For the reasons above stated it has heretofore been considered impractical to use escapements made in one piece with solid shoulders thereon.

Instead of having the shoulders b b' integral with the escapement-lever they may be separately constructed and pivoted or jointed to the lever, as in Patent No. 436,532, the increased length of the escapement being attended with certain advantages in such case. In view, however, of the satisfactory manner in which the lengthened escapement in one piece operates, and in view of the fact that it may be made at very much less cost than the escapement with pivoted shoulders or pawls I prefer the one-piece construction.

In order to permit the entrance of the upper shoulders d^2 into the magazine, the latter may be provided with suitable holes; but I prefer, as shown in Fig. 5, to provide the magazine in the under side with a continuous slot a^2 , extending transversely thereof to admit the shoulders d^2 . The transverse slot a^2 is of a width just sufficient to permit the entrance of the upper escapement-shoulders d^2 and of such width that it is impossible for the ears of the matrices to fall therein as they pass thereover. Were the slot of greater width, there would be danger of the matrices being arrested or retarded in their course to the delivery-point. As the

escapement-levers are seated in the grooves in the supporting-plate E directly under the magazine, and thus prevented from shifting laterally, it becomes possible to use escapements which are of uniform width or thickness, notwithstanding the variation in the width of the magazine-channels or grooves, and also possible to use the continuous slot a^2 without losing control of the matrices. 10 The lower shoulders d' may enter through a corresponding slot, or they may be seated beyond the end of the magazine-plate.

The provision of a transverse continuous slot admits the use of escapement-levers of 15 uniform width or thickness throughout the magazine. The channels a in the magazine are of varying widths, and heretofore it has been the practice to make the escapement pawls or shoulders of corresponding widths, 20 or, in other words, of a number of different widths in each magazine. The employment of escapements of uniform widths or thicknesses is a great advantage in that it simplifies the construction and greatly reduces the 25 cost of making and fitting the parts.

Having described my invention, what I claim is—

1. In a linotype-machine, the combination of a magazine, shouldered matrices, and escapement-levers having a length between its shoulders greater than the length of the matrices.

2. In a linotype-machine, the channeled magazine, in combination with shouldered 35 matrices, and escapement-levers each arranged to engage alternately the rear end and the forward end of the outgoing matrix.

3. In a linotype-machine, the combination of a magazine and matrices, with escapements, each having its front and rear ends arranged to engage respectively with the front and rear ends of the outgoing matrices.

4. In a linotype-machine, the magazine having longitudinal channels to guide the 45 matrices, and a continuous transverse slot in the under side to admit the escapements, in combination with the escapement-support

seated wholly on the outside of the magazine, and the pivoted escapements having their upper ends or shoulders projected into 50 and adapted to fill the slot in the magazine.

5. In a linotype-machine, the longitudinally-channelled magazine having a transverse slot therein, in combination with a series of pivoted one-piece escapements, each 55 having the lower end adapted to engage the matrices at the extremity of the magazine, and the upper end adapted to enter and fit the transverse slot.

6. In a linotype-machine, an oscillating 60 escapement arranged to engage at its front and rear ends successively with the front and rear end of each passing matrix.

7. In a linotype-machine, the combination of series of matrices and an escapement 65 adapted to engage at its lower end with the forward end of one matrix, and at the same time extend at its opposite end beyond said matrix in position to engage a following matrix.

8. In a linotype-machine, a magazine provided with longitudinal channels of varying widths, and with a transverse slot, in combination with a series of escapement-levers of uniform width arranged to act at one end 75 through said slot; whereby the escapements of uniform thicknesses are adapted to control matrices of different thicknesses.

9. In combination with a magazine having longitudinal channels, and a transverse slot 80 intersecting said channels, a series of escapement-levers of uniform thickness, and a support E with longitudinal grooves to receive the escapements; whereby the escapements are kept in proper operative relations to the 85 longitudinal channels.

In testimony whereof I hereunto set my hand, this 30th day of August, 1906, in the presence of two attesting witnesses.

JOHN R. ROGERS.
